CANDLEHOLDER

Pauline George Nelson, Staten Island, N. Y.

Application March 23, 1950, Serial No. 8,731

Term of patent 14 years

(Cl. D48—2)

To all whom it may concern:

Be it known that I, Pauline George Nelson, a citizen of the United States, residing in the city of New York, county of Richmond, and State of New York, have invented a new, original, and ornamental Design for a Candleholder, of which the following is a specification, reference being had to the accompanying drawing, forming a part thereof, in which:

Fig. 1 is a side elevational view of a candleholder, showing my new design; and

Fig. 2 is a cross-sectional view thereof taken on the line 2—2 of Fig. 1.

I claim:

The ornamental design for a candleholder, as shown.

PAULINE GEORGE NELSON.
